(57) **CLAIM**

We claim ornamental design for a firearm frame, as shown and described.

DESCRIPTION

FIG. 1 is a front perspective view of a firearm frame according to the present invention;

FIG. 2 is a rear perspective view of the firearm frame of FIG. 1;

FIG. 3 is a front view of the firearm frame of FIG. 1;

FIG. 4 is a rear view of the firearm frame of FIG. 1;

FIG. 5 is a right-side view of the firearm frame of FIG. 1;

FIG. 6 is a left-side view of the firearm frame of FIG. 1;

FIG. 7 is a top view of the firearm frame of FIG. 1;

FIG. 8 is a bottom view of the firearm frame of FIG. 1;

FIG. 9 is a top view of an opening for a magazine in the firearm frame of FIG. 1; and,

FIG. 10 is a bottom view of the opening for the magazine of FIG. 9.

The broken line showing is included for the purpose of illustrating portions of the firearm frame that form no part of the claimed design.
